Inventor
A. M. Strecker

By Clarence O'Brien

Attorney

UNITED STATES PATENT OFFICE.

ANDREW M. STRECKER, OF PHROSO, OKLAHOMA.

PRESS-WHEEL BOXING FOR GRAIN DRILLS.

Application filed February 12, 1926. Serial No. 87,847.

This invention relates to a wheel boxing construction for wheat or other grain drills, and has for its primary object to provide such a boxing that will prevent the passing 5 of dust, dirt, and other foreign matter between the wheel supporting axle bars and housings therefor, which would otherwise impair the efficient operation of the press wheels during the movement of the drill 10 over the ground.

Another and important object is the provision of such a wheel boxing that may be readily disassembled for repair or renewal purposes.

Other objects will become apparent as the nature of the invention is better understood, the same comprises the novel form, combination and arrangement of parts hereinafter more fully described and shown in the accompanying drawings and claimed.

In the drawing, wherein like reference characters indicate corresponding parts throughout the several views:

Figure 1 is a view in side elevation of a 25 press wheel unit for grain drills constructed in accordance with the present invention, the same being shown as actually associated through medium of a conventional spring support through the usual grain drill gang 30 press attachment bar.

Fig. 2 is a detail longitudinal section thru a press wheel boxing constructed in accordance with the present invention.

Fig. 3 is a view in end elevation of one 35 of the axle housing elements, included as an element in the invention.

Fig. 4 is a similar view of the other axle housing section, and

Fig. 5 is a perspective of a bar secured at 40 one end to the axle housing section and at its opposite end to said conventional attaching spring.

Now having particular reference to the drawing, 5 indicates the usual horizontal bar at the rear end of a Van Brunt or similar type of grain drill thru which the usual pairs of press wheels of a gang set are attached through medium of a conventional curvilinear band spring 6.

As is well known, a gang press for grain 50 drills consists of a plurality of press units, each unit consisting of a pair of assembled press wheels, that are to be attached to said horizontal bar 5 of the drill. For purpose

of illustration, it is only necessary that one 55 of these units comprising the gang be shown and described.

Such a unit consists of a pair of shaft 60 housings 7 and 8 to be arranged in end to end relation as clearly shown in Fig. 2, the adjacent ends of the sections being enlarged as at 7' and 8' respectively, the contacting faces of which are formed with central circular depressions 9 within which are arranged for free rotation, disks 10—10 upon 65 the inner ends of wheel supporting shaft sections 11—11 that are also freely rotatable within the housing sections 7 and 8.

The outer ends of said shaft sections 11—11 are reduced in diameter as at 12—12 while 70 mounted and secured thereon are the usual press wheels 13 of the said unit, the inner ends of the hub portions 14—14 of said press wheels loosely engaging within sockets 15—15 formed upon the outer ends of the housing sections 7 and 8 to prevent the passage of dust and other foreign matter between the shaft sections 11—11 and said housing sections 7 and 8.

One of the housing sections is formed at 80 its top side with a laterally extending circular lug 16 formed with a threaded opening for receiving the usual threaded nipple of a grease cup 17, said circular lug 16 adapted to be arranged within a semicircular depression 18 at the top side of the other housing section as clearly shown in Figs. 2 and 4.

The adjacent ends of said housing sections are formed with a plurality of radially disposed ears 19 that are formed with openings through which securing means are adapted to be extended in order that the said housing sections may be rigidly interconnected. Also, each housing section is formed at its inner side and inner end with a forwardly extending and upwardly inclined arm 20, that is formed throughout its length with a depression 21 for providing a socket for the inner end of a bar 22 when the housing sections are joined together, said arm and bar being provided with suitable openings as shown in order that the bar may be secured within the socket so provided. The forward end of the bar 22 is adapted to be connected in any desirable manner with the free end of the before mentioned curvilinear spring 6 that is secured at its opposite end to the hori-

zontal bar 5 over all conventional grain drills.

It will thus be seen that I have provided a highly novel, simple press wheel boxing 5 for grain drills that may be readily lubricated and that will be substantially dust-proof, thus permitting the drill to be operated under all conditions, and that will not require the continual cleaning of the 10 boxing that is now the case in other gang press units, and associated with grain drills.

Minor changes may be made in the invention without departing from the spirit and scope of the appended claims.

15 Having thus described my invention, what I claim as new is:—

1. In a boxing, a pair of complementary axle housing sections secured together at their inner ends, axles extending through 20 the respective sections, press wheels on the outer ends of the axles, disks carried by the inner opposed ends of the axles, the inner opposed faces of the housing sections having circular depressions formed therein in 25 which said disks are rotatable, an apertured lug extending laterally from the inner end of one of the axle housing sections, the adjacent portion of the inner end of the other housing section being cut out to receive said 30 lug, and a grease cup supported in the aper-

tured lug and adapted to communicate with said circular depressions.

2. In a boxing, a pair of complementary axle housing sections secured together at their inner ends, axles extending through 35 the respective sections, press wheels on the outer ends of the axles, disks carried by the inner opposed ends of the axles, the inner opposed faces of the housing sections having circular depressions formed therein in 40 which said disks are rotatable, an apertured lug extending laterally from the inner end of one of the axle housing sections, the adjacent portion of the inner end of the other housing section being cut out to receive said 45 lug, a grease cup supported in the apertured lug and adapted to communicate with said circular depressions, means connected to the axle housing sections whereby the same may be secured to the supporting bar of a grain 50 drill, said last mentioned means comprising a pair of complementary arms projecting forwardly from the inner opposed end portions of the axle housing sections, said arms being formed with complementary depressions 55 to provide a socket, and an attaching bar secured at one end within the socket.

In testimony whereof I affix my signature.

ANDREW M. STRECKER.
